Primary Examiner — Austin Murphy*(74) Attorney, Agent, or Firm* — Todd R. Miller(57) **CLAIM**

The ornamental design for a strip pad for an electronic device, as shown.

DESCRIPTION

FIG. 1 is an illustration of a perspective top view of the strip pad for an electronic device.

FIG. 2 is an illustration of a perspective bottom view of the strip pad for an electronic device.

FIG. 3 is an illustration of a bottom view of the strip pad for an electronic device.

FIG. 4 is an illustration of a top view of the strip pad for an electronic device.

FIG. 5 is an illustration of a front end view of the strip pad for an electronic device.

FIG. 6 is an illustration of a rear end view of the strip pad for an electronic device.

FIG. 7 is an illustration of a right side view of the strip pad for an electronic device; and,

FIG. 8 is an illustration of a left side view of the strip pad for an electronic device.
